(57) CLAIM

The ornamental design for a garment, as shown and described.

DESCRIPTION

FIG. 1 is a front view of a garment according to a first embodiment of the design;

FIG. 2 is a rear view thereof;

FIG. 3 is a right side view thereof;

FIG. 4 is a left side view thereof;

FIG. 5 is a front perspective view thereof;

FIG. 6 is a rear perspective view thereof;

FIG. 7 is a front view thereof shown in an environment of use;

FIG. 8 is an enlarged detail view of the portion 8 of the garment encircled in FIG. 4 with the pocket thereof shown in an opened position;

FIG. 9 is a front view of a garment according to a second embodiment of the design;

FIG. 10 is a rear view thereof;

FIG. 11 is a right side view thereof;

FIG. 12 is a left side view thereof;

FIG. 13 is a front perspective view thereof;

FIG. 14 is a rear perspective view thereof;

FIG. 15 is a front view thereof shown in an environment of use; and,

FIG. 16 is an enlarged detail view of the portion 16 of the garment encircled in FIG. 12 with the pocket thereof shown in an opened position.

The portions of the garment shown in dash-dash broken lines in FIGS. 1-16 do not form part of the claimed design. The dash-dash broken line showing of the arms, legs, and torso in FIGS. 7 and 15 is for the purpose of illustrating portions of the environmental structure and forms no part of the claimed design. The dot-dash broken lines shown in the drawings encircle portions of the garment that are illustrated in enlargements and do not form part of the claimed design.
